UNITED STATES PATENT OFFICE.

RICHARD GREENLEAF TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

PNEUMATIC WEFT DETECTOR FOR LOOMS.

Application filed September 22, 1925. Serial No. 57,916.

This invention relates to improvements in weft detectors for looms and it is the principal object of the invention to provide a detector operative to give an indication 5 upon substantial weft exhaustion so constructed that no portion thereof has direct contact with any part of the weft supply.

In the weaving of certain fabrics involving very fine yarn it is found that the supply of weft lasts for so long a time that the usual forms of weft detector abrades the yarn and causes ultimate failure of the same before the weft is exhausted. Various attempts have been made to develop detectors 15 to meet this condition, but all of them, so far as I am aware, require direct contact with some portion of the weft supply or carrier therefor.

In carrying out my invention I provide 20 means to secure an indication of weft exhaustion by means which will not come in contact in any way with the supply of weft and it is accordingly a further object of my invention to provide a pneumatic detector 25 to cooperate with a special form of bobbin so arranged that while sufficient weft for continued weaving is present a stream of air will be deflected, but as soon as the supply is depleted sufficiently to render replenishment 30 necessary the stream of air will be permitted to pass through an opening in the weft carrier and to move a member to indicate weft exhaustion.

It is a further object of my invention to 35 provide means for varying the strength of the air blast cooperating with the detected surface, the particular method shown herein involving an adjustment between the lay and the piston of the air compressor.

It is a still further object of my invention 40 to operate a pneumatic detector by air compressed through the action of the lay.

With these and other objects in view 45 which will appear as the description proceeds, the invention resides in the combination and arrangement of parts hereinafter described and set forth in the claims.

In the accompanying drawings wherein 50 I have shown a convenient embodiment of my invention,

Fig. 1 is a top plan view of my detector showing the same in detecting position with respect to a shuttle supplied with sufficient weft, parts being in section,

Fig. 2 is a vertical section taken on line 2—2 of Fig. 1 showing the stream of air deflected by a sufficient supply of weft,

Fig. 3 is a vertical section on line 3—3 of Fig. 1 showing the actuator lever moved to non-indicating position,

Fig. 4 is a vertical section on line 4—4 of Fig. 1 with parts broken away but showing the parts moved to indicating position and the lay on front center,

Fig. 5 is a horizontal section on line 5—5 of Fig. 4,

Fig. 6 is an enlarged longitudinal section through the end of the controller member acted on by the stream of air, and

Fig. 7 is a vertical central section through the air compressor showing the action of the spring in continuing to compress air after the lay has passed front center.

Referring to the drawings, it will be seen that I have provided a loomside 10 and a lay 75 11 of the usual form, said loomside supporting a replenishing mechanism 12, preferably of the multi-color type. The lay is slotted as at 13 for the passage of an expelled bobbin and carries a box back 14 which, together with the binder 15, forms a box for the shuttles.

In carrying out my invention I provide an air compressor C held in fixed position and having a piston 30 having a connector 85 rod 31 on which is slidably mounted a loose collar 32. A spring 33 is interposed between the collar and the piston and is strong enough to move the piston down when the collar descends. A lever 34 is pivoted on a 90 stud 35 secured to a bracket 36 and has driving connection with collar 32 at the forward end thereof. An upstanding arm 37 formed on the lever 34 is slotted as at 38 to receive a stud 39 adjustably fastened to said 95 arm. A roll 40 on the stud is positioned to engage a bunter 41 carried by the lay and an adjustable stop screw 42 on lever 34 engages a horn 43 of bracket 36 to limit movement of the roll toward the bunter under 100

influence of spring 44 interposed between the lever and the bracket to raise the piston 30.

By means of the mechanism thus far described the spring 33 is compressed on each forward stroke of the lay and serves to move the piston downwardly. Energy derived from the lay will be stored in the spring so that the latter will continue to 10 compress air while the lay is on front center and after it starts to move rearwardly.

A flexible tube 45 is pneumatically connected to the compressor and leads to a nipple 46 threaded in an opening 47 formed in 15 box back 14.

A stand 48 secured to the loom frame is provided with a cap 49 between which and said stand is mounted for free sliding movement a controller 50 the rear end of which 20 is cup shaped as at 51 (see Fig. 6). Said controller is provided with an offset portion slotted as at 52 and has secured thereto a collar 53 which receives the rearward thrust of a light spring 54 located between said 25 collar and the stand 48.

The slot 52 of the controller 50 is in vertical alignment with a slot 55 formed in the cap 49 so that under normal conditions 30 a vertically reciprocating actuator lever 56 is free to move from the slot 55 into the slot 52. An adjusting screw 57 mounted in the stand 48 determines the rear position of the controller.

In carrying out my invention I employ 35 a bobbin B having a horizontally disposed slot 58 which is in alignment with front and rear slots 59 and 60, respectively, formed in the walls of shuttle S. On the forward stroke of the lay the compressor 40 will force air through tube 45 and cause it to issue through slot 60 of the shuttle. So long as sufficient yarn for continued 45 weaving is on the bobbin the slot 58 will be covered and the air directed against the yarn will be deflected above and below the bobbin as indicated by the arrows in Figs. 1 and 2 so as not to strike the cup 51 of the controller 50. The latter will therefore permit uninterrupted downward motion of 50 actuator lever 56.

As soon as the weft becomes depleted enough to require replenishment the blast of air will pass through slot 58 in the bobbin and strike the cup 51 to move the same 55 forwardly until slot 52 moves out of alignment with slot 55 and a solid portion of the controller lies under the actuator lever 56. The latter is therefore prevented from having its normal downward motion and depresses a rod 61 connected to the replenishing mechanism to indicate the latter. For a further description of lever 56 and its connection with the replenishing mechanism reference may be had to Patent No. 65 1,030,748.

The cup 51 at no time comes in contact with the yarn, being spaced from the latter when the lay is on front center as indicated in Fig. 2. The lever 56 is timed to start down when the lay has almost reached 70 front center and the full incoming bobbin prevents the stream of air from moving the controller on a transferring pick under the lever at the time the latter starts down. A second indication is therefore prevented. 75 By means of the slotted adjustment of the roll 40 the amount of the lay motion used for compressing air may be varied to the end that the time during which the stream of air blows against the bobbin may be 80 changed with respect to the cycle of the pick. Any one of several known devices may be used to place the bobbins in the shuttle with the slots 58 horizontal.

From the foregoing it will be seen that I 85 have provided a detector operative upon the substantial exhaustion of weft, but operating in such a manner as at no time to have direct contact either with the supply of weft or the carrier therefor. Also, the time 90 during which the air blast is operative may be varied with respect to the cycle of the pick so as to come early or late with regard to the down motion of actuator lever 56. It will further be noted that the cooperating 95 elements which serve to give an indication of weft exhaustion are independent of the shuttle and the weft supply so that the latter may be in the form of a cop and not necessarily carried by a bobbin. 100

Having thus described my invention it will be apparent that changes and modifications may be made therein by those skilled in the art without departing from the spirit and scope of the invention, and I do not wish to be limited to the details herein disclosed, but what I claim is: 105

1. In a weft detector for a loom having a shuttle and a supply of weft therein, an element responsive to air pressure to indicate depletion of weft, and means to project a stream of air toward the supply of weft and the element, the latter being shielded from the action of the stream of air by a sufficient supply of weft and exposed to the action of the stream of air by a depleted supply of weft. 110

2. In a weft detector for a loom having a shuttle and a supply of weft therein, means to direct a stream of air toward the supply of weft, an element responsive to the stream of air located on one side of the weft supply, said means directing the stream of air toward the element from the other side of the weft supply, the element being shielded from the action of the stream of air by a sufficient supply of weft and exposed to the action of the stream of air to give an indication when insufficient weft is present. 115 120 125 130

3. In a weft detector for a loom having a shuttle and a supply of weft therein, an element movable by a blast of air to indicate depletion of weft, and means to direct a blast of air toward the supply of weft and the element, the latter being shielded from the blast by a sufficient supply of weft and exposed to the blast to respond thereto by a depleted supply of weft.
4. In a weft detector for looms having a shuttle and a supply of weft therein, means defining an air passage extending through the shuttle, said passage being normally closed by a sufficient supply of yarn and open when the yarn supply is depleted, an element responsive to fluid pressure to indicate weft exhaustion located at one side of the passage, and means to project fluid under pressure through the passage to actuate the element when the passage is opened by a depleted weft supply.
5. In a weft detector for looms having a shuttle and a supply of weft therein, means out of contact with the supply of weft at all times to direct a blast of air against said supply of weft, and a movable device located on the side of the weft supply opposite said means, the supply of yarn deflecting the blast of air away from said movable device when sufficient yarn is present and said blast of air moving the movable device when insufficient yarn is present.
6. In a weft detector for looms having a shuttle and a supply of weft therein, a movable member adjacent the shuttle and weft supply but out of contact with the latter at all times, and means located on the opposite side of the shuttle from said movable member to direct a blast of air against the weft supply, said means being out of contact with the weft supply at all times, the blast of air being deflected from said member when a sufficient supply of weft is present and the blast of air moving from the means through space previously occupied by weft to the movable member to move the latter to give an indication of weft exhaustion when insufficient weft is present.
7. In weft detecting mechanism for looms, a bobbin having an opening therethrough normally covered by a sufficient supply of weft and uncovered when the weft is depleted to an extent rendering replenishment necessary, means located on one side of the bobbin to blow a blast of air through the opening at the time of substantial exhaustion, and means located on the other side of the bobbin and movable by the blast of air passing through the bobbin to indicate exhaustion of weft.
8. In weft detecting mechanism for looms, mechanism to indicate weft exhaustion, a bobbin having an opening therethrough normally closed when sufficient yarn is present but uncovered when the yarn is depleted, and means to cause a blast of air to pass through the opening of a depleted bobbin and actuate said mechanism.
9. In a weft detector for looms, mechanism movable to indicate weft exhaustion, means to direct a blast of air toward said mechanism, and a bobbin interposed between said indicating mechanism and the means and having an opening normally covered by a sufficient supply of weft but uncovered when the weft is depleted, said slot in the bobbin being in alignment with said mechanism and means and said mechanism being movable by the blast of air when the opening is uncovered.
10. In a weft replenishing loom, a lay, a shuttle thereon, a supply of weft carried by the shuttle, a member movable to indicate weft exhaustion, means to direct a blast of air through the shuttle to move said movable member when the supply of weft is depleted, and means to cause said blast of air to continue after the lay reaches the limit of its forward movement.
11. In a weft replenishing loom, a lay, a shuttle carried thereby, a supply of weft located in the shuttle, a member out of contact with the yarn at all times and movable to give an indication of weft exhaustion, mechanism to cause a blast of air to strike the movable member when insufficient weft is present, and connections between the lay and the mechanism to continue the blast of air after the lay reaches the limit of its forward movement.
12. In a weft replenishing loom, a lay, a pneumatic detector, an air compressor, connections between the lay and the air compressor to operate the pneumatic detector, and means to vary the time of operation of said connections between the lay and the compressor to vary the time at which said compressor operates with respect to the movement of the lay.
13. In a pneumatic weft detector for a weft replenishing loom, a controller to indicate weft exhaustion and occupying one position when sufficient weft is present and occupying another position when insufficient weft is present, said controller having a surface responsive to air pressure, a bobbin, and means to direct a stream of air against the bobbin and toward the responsive surface, said bobbin when supplied with sufficient weft deflecting the air away from the controller and said bobbin being so formed that when insufficient weft is thereon air will reach the surface responsive to air pressure to cause said controller to occupy the position to indicate weft exhaustion.
14. In a pneumatic weft detector for a weft replenishing loom, a controller to indicate weft exhaustion and occupying one position when sufficient weft is present and oc-

cupying another position when insufficient weft is present, said controller having a surface responsive to air pressure, a bobbin, and means to direct a stream of air against the bobbin and toward the responsive surface, said bobbin having a hole therein normally covered when sufficient weft is present but uncovered when the supply of weft is sub- stantly exhausted to permit air to pass to the surface responsive to air pressure to cause said controller to occupy the position to indicate weft exhaustion.

In testimony whereof I have hereunto affixed my signature.

RICHARD GREENLEAF TURNER.
